ADVERTISEMENT SIGN

Application filed October 5, 1929, Serial No. 397,644, and in Great Britain October 10, 1928.

This invention relates to advertisement signs and has for its object to provide means whereby an animated effect is imparted to a sign without any relative movement occurring in the sign.

This object is attained by utilizing the known phenomenon resulting from superposing two transparent lined screens and causing relative movement to take place between them, and according to the invention two laterally spaced lined screens, herein-after referred to as "grids" are interposed between the sign proper and the observer, so that on movement occurring between the sign and the observer the sign appears to be alternately cut off from and brought into view, the particular effect obtained depending on the arrangement of the screen lines.

The invention will now be described with reference to the accompanying drawings which show various examples of construction of the sign according to the present invention. In the said drawings:

Fig. 1 is a cross section of a form of construction wherein the grids are in the form of two openwork grids spaced from each other and from the sign proper.

Fig. 2 is a partial plan view of Fig. 1.

Fig. 3 is a cross section of a form of construction wherein one grid only is used.

Fig. 4 is a partial plan view of Fig. 3.

Fig. 5 is a cross section of a further form of construction wherein one grid only is used.

Fig. 6 is a cross section of a device for adapting the present invention to an existing sign.

Fig. 7 is a partial face view of a modified form of grids and sign.

Fig. 8 is a cross section of a further modified form of sign wherein a double reflection occurs.

Referring more particularly to Figs. 1 and 2 of the drawings, 1 indicates the sign casing, 2 the sign proper and 3 an angled mirror. Two grids 4, 5 are placed below the sign proper 2, and are spaced apart laterally from each other and from the sign proper or its image. The slots in each grid may be straight and parallel to each other, or they may be wavy and parallel or wavy and op-

posed to each other; and either two similar or two different grids may be used together.

With this construction movement of either the sign or the observer gives an animated effect to the image of the sign 2 owing to the angle of vision between the observer and the sign continuously changing as the relative movement takes place, and so causing the two grids 4, 5 to take up positions relatively to each other which are constantly changing as the movement continues. For example in the case of two similar grids each having vertical slots, the effect will be that the sign is being intermittently illuminated. Again, one or both grids may comprise wire mesh or gauze, which combination gives a water wave effect.

Further effects may be obtained with this arrangement merely by varying the angles of the slots in the grids, or by making them of varying shapes. For example, by having the slots of one grid at an angle to those of the other grid, a running up or down effect is obtained; by having the slots of herringbone formation and arranging the one grid so that its formation is opposed to that of the other, one half of the sign appears to have ascending lights and the other descending lights; by arranging the slots in opposed key pattern, that is to say a kind of rectangular zig-zag, a scintillating effect is obtained.

Figs. 3 and 4 show another form of this construction in which one grid 6 only is used, the other grid being incorporated with the sign proper 2 by drawing lines over the sign to correspond with what would be the other grid. The single grid form is the preferred form of the invention as it allows individual effects to be given to different portions of the sign.

Fig. 5 shows a modified form of the single grid form of sign with the grid 6 arranged in front in a vertical plane, and the sign 2 in a horizontal plane. This form of sign gives a greater distance between the sign and the grid, as will be seen from a comparison of the lines of vision shown in dotted lines in the various pertinent figures; and it gives a more rapid movement of the shadow.

bands. Obviously the positions of the grid and sign may be reversed if desired. It is preferable with this form to provide a proscenium 7 in order to cut off the surrounding light from the vertical member of the combination.

Fig. 6 shows a device for adapting the invention to an existing reflex sign. This device comprises a casing 8 which is adapted to fit over the top of the reflex sign, and rest thereon by means of a flange 9. The upper portion of the casing 8 has a groove formed by two flanges 10, 11 to receive either the sign proper or a grid. To apply this device, 10 the existing sign proper is lined according to requirements as shown in Fig. 4, and inserted between the flanges 10, 11, while a grid is placed in the position in the sign casing originally occupied by its sign proper. 15 Or, the lined sign proper is returned to its original position and the grid inserted between the flanges 10, 11. The device may be secured in position by nuts and bolts as indicated diagrammatically at 12, 13. Alternatively, 20 the sign proper may be left unlined and two spaced grids arranged in the casing 8 which may be secured to the top of the sign as shown, or it may be secured to the front of the sign. If desired the double 25 grid may be manufactured and sold in strip form for placing in front of any kind of sign to impart animation thereto.

To adapt a reflex sign having an open top with the sign proper in front, the device 30 shown in Fig. 6 with a grid between the flanges 10, 11 may be used, the sign being lined as desired, while the device is applied as above set forth.

With all the above forms of construction, 35 the grids are preferably arranged underneath the sign proper so as to be out of sight, their reflection only being seen. This tends to add to the general effect of the sign on the mind of the observer, the lines being less 40 obvious to the eye.

According to further arrangements, the one grid may be formed by drawing lines 45 on the face of the mirror of the sign, or by producing bands only of silvering on the back of the mirror. With this form the second "grid" may be obtained by drawing lines on the front of the mirror.

In the form shown in Fig. 7, 14 is a strip 50 of glass having a lined sign 15 formed at its rear, while the front side 16 of the glass is lined with parallel lines. This example shows the advantage of incorporating one grid with the sign proper, for different portions of the sign may be given different effects, 55 by drawing the lines on the letters as shown: in the "S" the resulting shadow band takes a sinuous course along the letter; in the "I" it takes an up or down course; and in the "G" a curved course. 60 Other examples of the varied effects obtain-

able with this form of "grid" consist in drawing broken vertical lines on the sign with the "breaks" of adjacent lines staggered, for example so as to give a minute check pattern, which with a parallel lined grid produces a sparkling or scintillating effect; drawing wavy lines made up of series of concentric segments oppositely disposed, which with a parallel lined grid gives the effect of spreading ripples.

Again by using a plate of fine hamered glass having a somewhat mottled appearance, and thus giving the glass a large number of refractive points, for the sign base, the use of one grid only gives an animated effect to the sign when relative motion takes place. Again, the grids may consist of transparent plates with lines drawn thereon. However it is preferred to use an open-work grid where possible as there is no chance of refractive or reflective effects with such, as there is with transparent plates such as glass plates.

It will be observed that the above "static" signs have been described with reference to relative motion sideways, in all of which cases the direction of the slots tends from angular to vertical. However, in the case of oncoming relative movement, such as occurs when a sign projecting at right angles over a pavement is approached, the direction of the slots tends from angular to horizontal, the latter giving the pure intermittent lighting effect when two similar grids are used. A combination of sideways and oncoming sign may be obtained by arranging the slots or lines at an angle between horizontal and vertical, for example 45 degrees.

According to a further form of the invention for use with an interchangeable letter sign, the letters are cut out in the form of stencils with the grid lines incorporated in the letters, the sign proper comprising a sheet of coloured translucent material, such as coloured glass. With this form the usual stencil effect is eliminated as the lines serve to hold the stencil together and thus render the usual joining pieces unnecessary. Alternatively, the letters and lines may be formed on glass or the like so that the stencils and signs are incorporated in single members. In both the foregoing examples a vertically lined grid is preferably used as the second grid.

Fig. 8 shows a modification of the invention which is adapted to give light bands in place of shadow bands. According to this form, a sign lined with reflecting lines is formed on a mirror 17 arranged substantially horizontally in a casing 18, while a grid 19 of reflecting material, such as a slotted plate of stainless steel, is arranged at a distance above the sign. An angled mirror 20 reflects the sign 17 and grid 19.

In use, the light first strikes the grid 19 and sign 17, from each of which members it is reflected to the mirror 20 which again reflects the composite image to the observer.

5 The image appears as a sign with light bands which move according to the movement of the observer. Obviously the above form may be used to give shadow bands also, by forming the sign lines and grid in non-reflecting black.

10 The grid or grids and/or the sign proper may be arranged for relative movement by mechanical means; for example, a pendulum may be hingedly connected to a grid, so that 15 as the pendulum oscillated, a reciprocating movement would be imparted to the grid. Where two grids are used the point of suspension of the pendulum is located substantially midway between the two grids, the 20 upper grid being hingedly connected to an extension of the pendulum rod, so that the grids are moved in opposite directions as the pendulum oscillates.

We claim:—

25 1. An animated reflector sign comprising a casing, a sign proper in said casing, two laterally spaced and stationary grids adjacent said sign proper and an angled mirror in said casing adapted to reflect the 30 images of the said sign proper and grids through an opening in said casing.

2. A sign according to claim 1, the sign proper and grids being on the one side of the mirror.

35 3. A sign according to claim 1, wherein the sign proper is in front of the mirror.

4. A sign according to claim 1, and a reflecting surface behind the sign proper, the sign casing being positioned so that the light 10 first strikes the grids and sign proper and is then reflected on to the mirror.

15 5. A sign according to claim 1, a reflecting surface behind the sign proper and reflecting surfaces on the grids, the sign casing being positioned so that the light first strikes the grids and sign proper and is then reflected on to the mirror.

6. A sign attachment adapted to fit over 20 existing signs, comprising an open casing, two stationary spaced grids in said casing, and means for securing said casing over the existing sign.

In witness whereof we have signed this specification.

THOMAS LAMB.
W. REID SHARP.
